(57) **CLAIM**

The ornamental design for a compact disc wallet with exterior storage, shown and described.

DESCRIPTION

FIG. 1 is a front perspective view of a compact disc wallet with exterior storage showing our new design;

FIG. 2 is a bottom plan view thereof;

FIG. 3 is a front elevation view thereof;

FIG. 4 is a right elevation view thereof;

FIG. 5 is a rear elevation view thereof;

FIG. 6 is a left elevation view thereof;

FIG. 7 is a bottom plan view thereof;

FIG. 8 is a front perspective view thereof, shown in an open position; and,

FIG. 9 is a front perspective view thereof, shown in an open position.

The broken line showing is included in all Figs. for the purposes of illustrating environment and forms no part of the claimed design. The surface textures shown in fragment in all Figs. represent overall surface textures applied within the defined areas.
